UNITED STATES PATENT OFFICE.

ROLLAND H. NEAL, OF LAKE CITY, MINNESOTA.

AEROPLANE.

1,170,777.

Specification of Letters Patent.

Patented Feb. 8, 1916.

Application filed September 18, 1915. Serial No. 51,492.

To all whom it may concern:

Be it known that I, ROLLAND H. NEAL, a citizen of the United States, residing at Lake City, in the county of Wabasha and State of Minnesota, have invented certain new and useful Improvements in Aeroplanes, of which the following is a specification.

My invention relates to improvements in aeroplanes, its object being to provide an improved method of propulsion for the aeroplane taking the place of the ordinary propellers. To this end I provide a plurality of air suction and discharge tubes so constructed and arranged as to drive the aeroplane forward or to raise the same as the air is drawn into and discharged from said tubes. I claim by means of my improved method of propulsion and features of construction to be able to secure a greater speed and stability than is possible with the ordinary construction of aeroplane.

To this end the invention consists in the features of construction, combination, and arrangement of parts hereinafter described and claimed.

In the accompanying drawings forming part of this specification, Figure 1 is a side elevation of an aeroplane constructed in accordance with my invention; Fig. 2 is a plan view of the same; Fig. 3 is an end view partly broken away; Fig. 4 is a longitudinal section of one of the propulsion tubes; Figs. 5 and 6 are detail views of the rudder; Fig. 7 is a perspective view of the modified construction; and Fig. 8 is an end view of the same.

Referring to the drawings A represents suitable framework supporting a rigid top plane 2. Extending longitudinally of the framework and supported thereby is a tube 3. The rear end 4 of said tube flares outwardly toward the rear end of the machine. A tapered cone 5 is centrally supported in the flared end of the tube as by means of the framework 6. Centrally supported in the tube 3 in front of the flaring portion 4 is a pair of fans 7 and 8, the fans having journal support 9 and being connected with a suitable engine 10 through the medium of pins 11 and shaft 12. The fan 7 is located in front of the fan 8 and the blades of the fans are so positioned that in the operation thereof the fan 7 will suck the air into the tubes 3 and the fan 8 will force the indrawn air outwardly through the flared end of the tube around the central cone 5.

Arranged at the sides of the longitudinal tube are the upright tubes 13 constructed similar to the longitudinal tubes with the smaller end of the tubes opening at the top of the plane 2 and the flaring ends of the tubes opening downwardly. Fans 14 and 15 corresponding with the fans 7 and 8 are supported within the tubes 13 and connected through the pinions 16 and shaft 17 with a suitable engine 18. A rudder 19 is secured to the rear of the machine upon a shaft 20 which is adapted to be turned through the medium of a rod 21 having offset connection at one end with a lever shaft and at the other end as shown connected with a suitable foot lever. For the purpose of tilting the machine I provide planes or blades 22 mounted on a horizontal shaft 23 and operatively connected as by a rod 24 with a foot lever.

In operation the aviator will in driving forward connect the engine 10 with the fans 7 and 8 and in raising the aeroplane connect the engine 18 with the fans 14 and 15. The rudder 19 will be used in the ordinary manner to steer the machine in its forward travel and the tilting planes or blades 22 to direct the machine in its upward travel. In the forward movement of the aeroplane or in the lifting thereof the air will be drawn into the horizontal or the vertical tubes as the case may be, being sucked in the smaller ends of the tube by the indrawing fan and forced out of the flared discharge end of the tube by the fan 8 or 15, as the case may be. As the air is forced out through the flared end of the tubes it will be spread around the cone 5 covering a larger area in the discharge than if the tube was unflared and assist in the propulsion and stability.

In the modified construction shown in Fig. 7 I employ two longitudinal pipes instead of one, and in order to accommodate the longitudinal pipes arrange the vertical pipes in front of each other, as shown best in Fig. 7. The construction of the tubes is the same in the modified as in the preferred construction.

I claim:

1. An aeroplane of the class described comprising a framework and a rigidly supported plane, a propulsion tube extending longitudinally of said aeroplane and having an enlarged rear end, a tapered cone centrally positioned in the enlarged end of said tube, and means for drawing the air into the

smaller end of said tube and forcing it out of the flared end around said cone.

2. An aeroplane of the class described comprising a framework and a rigidly supported plane, a propulsion tube extending longitudinally of said aeroplane and having an enlarged rear end, a tapered cone centrally positioned in the enlarged end of said tube, means for drawing the air into the 10 smaller end of said tube and forcing it out of the flared end around said cone comprising a fan positioned toward the inlet end of the tube, and a discharge fan at the rear of said inrawing fan, and means for actuating said fans.

3. An aeroplane of the class described comprising a framework and a rigidly supported plane, a propulsion tube extending longitudinally of said aeroplane and having 20 an enlarged rear end, a tapered cone centrally positioned in the enlarged end of said tube, means for drawing the air into the

smaller end of said tube and forcing it out of the flared end around said cone, and a plurality of similar suction tubes extending 25 vertically of said aeroplane with the smaller ends opening into the top of the plane and the flaring ends at the bottom thereof.

4. An aeroplane of the class described comprising a framework and a rigidly supported plane, a propulsion tube extending longitudinally of said aeroplane and having an enlarged rear end, a tapered cone centrally positioned in the enlarged end of said tube, means for drawing the air into the 35 smaller end of said tube and forcing it out of the flared end around said cone, and vertical and horizontal guiding rudders for said machine.

In testimony whereof I affix my signature 40 in presence of a witness.

ROLLAND H. NEAL.

Witness:

H. S. JOHNSON.
